UNITED STATES PATENT OFFICE.

VASSAF KADRY, OF CONSTANTINOPLE, TURKEY, ASSIGNOR TO UNDERWOOD TYPE-WRITER COMPANY, OF NEW YORK, N. Y., A CORPORATION OF DELAWARE.

TYPE-WRITING MACHINE.

1,213,880.

Specification of Letters Patent. Patented Jan. 30, 1917.

Application filed January 15, 1914. Serial No. 512,244.

To all whom it may concern:

Be it known that I, VASSAF KADRY, a subject of the Sultan of Turkey, residing in the city of Constantinople, in the Empire of Turkey, have invented certain new and useful Improvements in Type-Writing Machines, of which the following is a specification.

My invention relates to typewriting machines, and more particularly to the kind of machine which is adapted to write languages of the Arabic group, wherein the letters are extremely complicated, and wherein certain letters occur in several forms, dependent upon whether or not they are written to connect with the letters immediately following or preceding them, or with both the following and preceding letters. It has hitherto been supposed that to build a typewriting machine which would write such languages, the machine should theoretically include upward of eighty characters, besides punctuation marks; and in such machines as have actually been built, over ninety characters have been included; but such machines have failed of general adoption and use. In addition to having a large number of characters, such machines as have been built in the attempt to write such a language, have included a special escapement mechanism, including double and single-step feed-dogs. Even with such complex escapement mechanism, it was found that some letters failed to connect properly, or overlapped so as to mislead the reader, or were otherwise misplaced. Such machines also, owing to the incomplete spacing adjustments, made the letters overlap very badly and become otherwise disarranged and undecipherable at times.

According to my invention, the typewriter may include types which will all have uniform width, and of which types the separately written elements or impressions may be so connected or joined upon the work-sheet as to represent complete letters, and even syllables, and in fact, whole words, in the cursive style which has now become the standard official system of printing in the Ottoman Empire. The types which print this alphabet, or system of elements, as I have stated, are all of uniform width, and only a very slight and unobjectionable

variation (if any) in the printing is produced by my machine from the standard printing of the aforesaid standard Ottoman system; such variation (if any) being of no importance, and lying mainly in the lengths of the connecting lines between the successively written types or elements. The loops and points, which are the most characteristic features of such languages, may all, according to my invention, occupy the standard positions and be of the standard size set forth by said government for types of a given pitch. Furthermore, I have found that it is practicable to employ the standard letter-feeding pitch of one-tenth of an inch, usual in typewriting machines, such as is best represented by the Underwood typewriter.

In addition to reducing or eliminating the necessity for a variable escapement for the typewriter carriage, I have found it practicable to greatly reduce the number of types or elements required in the machine for typewriting the given complete characters. I cause certain types not only to print each a full letter, but I also contrive so to print each of such letters that it may connect with a subsequently written or successive letter or sign, and, when the succeeding elements are so connected on the work-sheet, they will read as a single letter.

Many of the dots I write by means of "silent" keys (which do not feed the typewriter carriage); and yet I have been able to so arrange the alinement of the printing surfaces of the type elements that the number of such silent keys is reduced to a minimum, while they will print in conventional form the modifications of the various letters which are used under different circumstances.

The writing types, characters and elements which I use in this invention may be formed on typewriter type-blocks of standard build, with two characters on each type-block, so that in a machine (as the Underwood) provided with a case-shift mechanism, each typewriter key is capable of printing from its connected type-block two characters, depending on the operation of the case-shift mechanism. I frequently find it convenient to cause the lower case to

write a letter which is to stand alone, and the upper case to write a letter which is to be used as a connecting letter, so-called; or I reverse this arrangement.

5 According to my invention, it is possible to write not only Arabic, but also Turkish, Persian and Hindustani, all with the same machine, and usually without any alteration of the types, escapement or silent keys, 10 whereby the capacity of the machine is made very great. To build a machine to write in as many as four languages of this kind has hitherto been supposed to be impossible. It will therefore be seen that my invention 15 is one of great utility, in that it permits the writing of several languages of the Arabic group on a single machine, and further, said machine can have such a small number of keys that it may be of the front-strike 20 type, wherein the writing is visible during the operation of the keys.

It has hitherto been supposed that it was impracticable to construct typewriters to write such complicated languages unless a 25 large number of really necessary characters were omitted. For instance, in prior machines, no comma or period was provided, as distinguished from the points which are used in association with letters, so that such 30 writing as was produced by said machines was inaccurate and often misleading. Also such machines were not provided with the letter "sin" connecting only on the left, or the letter "sin" non-connecting or connecting 35 both on the right and the left. This required the writing to be both misleading and inartistic. Moreover, such machines could not write such common combinations 40 of letters as are necessary in writing the word "Allah", for example. Where such machines were able to write such a word, a special type was provided which wrote all the letters at one stroke except the initial 45 "elif" of the word "Allah". Such examples of the limitations of prior machines might be multiplied to a considerable extent.

It is one of the objects of this invention to overcome these difficulties.

50 Other features and advantages will hereinafter appear.

In the accompanying drawings, Figure 1 is a perspective view of so much of a type-writing machine as is convenient for illustrating an escapement mechanism for use 55 with my invention. Fig. 2 is a plan view of the keyboard of the same, showing the silent keys with key levers in full lines and the escapement operating keys having levers in dotted lines. Fig. 3 shows the characters 60 of the keyboard, and also shows said characters in various specimen kinds of combinations. In said figure, the characters begin at the upper left-hand corner and run downward in the successive columns, and

65 said characters are arranged in the same order as those on the keys of the keyboard, beginning with the upper row on the top bank of keys at the right, then on the second row of characters on the said top bank (also beginning at the right) and so 70 on through the keyboard.

The silent key mechanism which forms the principal part of the mechanism shown in Fig. 1 is that shown in the patent to Helmond No. 827,726, August 7, 1906, although any of the silent key mechanisms shown in the following patents might be used: Wagner No. 660,231, October 28, 1900; Helmond and Kayle No. 730,456, June 9, 1903; Kellogg No. 745,356, December 1, 1903; Wagner No. 759,780, May 10, 1904; Wagner No. 12,465, reissued March 27, 1906; Kunath No. 827,735, August 7, 1906; Kunath No. 843,828, February 12, 1907; McLaughlin No. 850,846, April 16, 1907; Mac- 85 Dermott No. 974,505, November 1, 1910.

The sign 1 on the key lever 145 shows the sign which the type 141 operated by said key lever will print. Said sign is used to denote the very broad sound of ah. Said 90 sign is intended to be usually placed above a letter such as the letter "elif" 10. It is usually desirable not to have the carriage feed when said sign 1 is printed. To accomplish this, the type 141 is fixed on a type-bar 142 mounted on a fulcrum rod 143 and engaged by a bell crank 144, the latter connected to a lever 148 having the key 146 and pivoted at its rear end at 147. The levers and bell cranks for an ordinary type are indicated at 148 and 149, and operate a type-bar 150. The depression of any key carries down its lever and vibrates the bell crank forwardly, thereby throwing the type-bar 95 rearwardly, the type striking through a ribbon 151 against the front side of a platen (not shown).

Each of the series of type-bars has a heel 152, which strikes against a curved universal bar 153, and moves the same rearwardly, 110 the universal bar being fixed to a horizontal frame 154 which in said machine is suitably guided for rearward and forward movements. Upon said frame is usually fixed a slotted actuator 155 which engages a wrist 156 provided upon the short arm 157 of a lever 158, whereby the latter is caused to carry up and down a vibrator 159 through which is threaded the ribbon. The ribbon is vibrated by said lever at the actuation of any type key, including the accent key. Said universal bar is also utilized to effect the feeding of the paper carriage, which in the present machine feeds to the right, inasmuch as Arabic and the other languages written by this machine are read to the left. The paper carriage includes a rack 160 meshing with a pinion 161 connected to an es- 115 120 125

capement wheel 162, with which coöperate the usual spacing and detent dogs 163 and 164, said dogs being mounted on an upright rock arm or carrier 165. The backward movement of said carrier is effected in this instance by means of an interponent comprising a plate 166 having at its upper end a head 167. One side of the latter receives the impact of a tappet 168 mounted upon the rear edge of the universal bar frame 154, and the other is in contact with a screw or adjustable abutment 169 threaded into the upper portion of the dog carrier 165, thereby to regulate the stroke imparted to the latter through the interponent 167 to secure accurate and rapid feeding of the carriage. The universal bar under normal conditions operates said interponent and dog carrier at each rearward movement of each ordinary type-bar, so as to effect the usual letter-feeding movement of the carriage. Said interponent is movable to ineffective position by the silent keys, so that said silent keys are ineffective on the escapement mechanism. For this purpose said interponent plate is secured at its lower ends by means of screws 170 upon a vertical slide 171 mounted upon the dog carrier. The plate 166 is yielding and presses lightly against the screw 169, the latter having a rounded end to engage the head 167.

The slide 171 is provided with a projection 172, whereby it may be pulled down, this movement being effected by an arm 173 having a lip 174 normally standing over said projection 172, said arm being fixed upon a rock shaft 175 suitably mounted in the framework of the machine and being provided near its ends with operating arms 176 having pins 177 engaged by slots 178 formed vertically in the upper ends of links 179, each of said links being connected to its silent key lever 145. Whenever any ordinary key lever 148 is depressed, its type-bar is swung up to the universal bars operated so that the ribbon is vibrated into effective position and the dog carrier is also swung backward by means of the interponent 167; but when any idle key 145 is depressed, its link 179 is drawn down, vibrating the arm 176 and rocking the shaft 175 and arm 173, the lip 174 on the latter carrying down the projection 172 and slide 171, and hence withdrawing the interponent 167, so that the movement of the universal bar 153 is ineffective to operate the dog carrier 165. The provision of the slots 178 in the link 179 enables any link to rock the shaft 175 independently of the others. A counterweight 180, or other means, may be provided for returning said shaft to normal position. A spring 181 provided upon the dog carrier engages an ear 182 upon the slide 171 to lift the latter to normal position independently

of the keys 146. The slide 171 is guided by means not material to the present invention.

The numerals 1, 2, 3, 4, 5, 6, 7, 8, and 9 are shown in Fig. 3 at 2, 3, 4, 5, 13, 14, 6, 7, and 8. The key bearing the characters 1 and 10 is a silent key (viz., a key not operating the letter-feeding mechanism), and the character 1 is the sign "met" which is used over the letter "elif" 19, to give it the broad sound of a as in "Allah." The other sign on this key is explained below. The dots on the keys 28, 48, and 67 are to be placed over or under other characters in general, and consequently are on silent keys, that is, they are like the key 1 and do not operate the letter-feeding escapement. The key 9 is also a silent key and prints the sign of "teshdid" which is used for emphasis, and also bears the character "hemze," which last is a letter having the sound of ee.

I find it advantageous to form certain letters by combining two characters, which characters may either be printed by two letter-feeding keys or may be formed by operating a letter-feeding key and a silent key. For example, I provide the sign 17 which is commonly used as a comma in Turkish and Arabic, and this may be combined with the sign 69 to form the Persian or Hindustani letter having the sound of eh, this combination being shown in Fig. 3 at 95 the right hand of 17 wherein the comma 17 is combined with the sign 69. At 20 is shown "kaf," which is used either separately or as a terminal connecting letter. It is illustrated at the right as used separately in 100 the word "bak." It is also shown as a terminal connecting, as in the word "balk." The letter connecting "liam" is shown at 21 in said Fig. 3 and is illustrated as combined with other letters to form the word 105 "lefen" at the right thereof and also with two slanting lines to indicate the sound ch or k of Persian or Hindustani. The letter connecting "elif" is shown at 22 where it is illustrated as combined with dots (under the 110 connecting character 69) in the word "Turkia." The letter "liam mim" is shown at 25 where it is combined in the word "elma." Terminal "liam" is shown at 26 and the connecting terminal form at 36. . 115

The 6th, 7th, 8th, and 9th letters of the Arabic alphabet are formed from the 29th character in Fig. 3 which is combined with dots as shown therein to form various letters. Without a dot it is illustrated in the word "hakim"; with one dot above it, it is shown in the word "khas"; and with three dots below it it is shown in the word "chare". The second, third, fourth and fifth letters of the alphabet are produced from the 30th character of said figure according to the 120 number of dots and method of combining said character. Said 30th character when

combined with "liam" 21 makes an independent "l" (which is used in Persian and Hindustani as an independent "liam"), and is illustrated at the right hand of said character 30.

- The letter "connecting sod" is formed by printing the 31st character. With one dot above it, as shown at the extreme right opposite said character 31, it produces the sound of d as in the word "deleat" shown therein. This character "sod" is shown in 31 as combined with the independent letter "noon" (omitting the dot in said "noon") which is shown at 66 and thus forms the independent letter "sod" shown on the lower line at the right of said character 31 where it is also illustrated in the word "khas". Said letter "sod" is also illustrated in the word "sedaret" at the right of Fig. 3 at 31. Connecting "ayin" is shown at 32 in said figure where it is illustrated at the right of the character 32 in the word "ilm", also in the word "ghalib." Connecting "ef" is shown at 33 in Fig. 3 without a dot; with one dot above it, it is illustrated as part of the word "fark". With two dots above it as shown in the top line opposite 33, it combines as shown in the bottom line opposite said figure to give the sound of k as in "kalmac". Said character 33 may be combined with the character 30 to form the letter f as shown opposite 33, and with two dots placed above said combination forms the letter "kaf" as shown in the line above said 33. Connecting "sin" is seen at the right of 34 forming the word "sema." With three dots above it, said letter "sin" gives the sound of sh as shown in the word "shan" at the right of 34. This letter "sin" may be combined with the letter "noon" (lacking the dot) to form the independent letter "sin" as shown at the right of 34 and may be caused to give the sound of sh by placing three dots above the "sin" part as illustrated at the right. Connecting "mim" is shown at 37 and is illustrated as part of the word "hamal." Medial connecting "liam" is shown at 39. Connecting "te" as shown at 40 without the dot is illustrated at the right in the word "taraf." With the dot written in, it is often called "the" and gives the sound of z as in the word "zarf." Connecting "te" which connects on both sides as shown at 41, is illustrated in the word "matloub" at the right. Connecting terminal "kiaf" is shown at 43 and is illustrated as it occurs in the word "melek" at the right of 43. Connecting terminal "liam elif" is shown at 44, and is illustrated as forming part of the word "imla." Connecting "mim-elif" is shown at 45, and is illustrated as forming part of the word "osmanie." Non-connecting "ha" is shown at 46 and is illustrated in the word

"sabah." A dot may be added to this to give the sound of kh, j, or ch.

Non-connecting "ayin" as shown at 47 is illustrated as forming part of the word "matah". Connecting "ha" is shown at 49 where it connects both sides in the word "Mohammed". Said character 49 may be combined with dots to give various sounds. Connecting "sod" as shown at 50, is illustrated as forming part of the word "mesarif". Said letter "sod" may be employed with one dot to give the sound of z, d, etc.

The character 51 is a sign which may serve to connect with another, and when combined with various dots in this way represents various sounds, as for example, in the word "bab" which is illustrated at the right.

Connecting "ayin" as shown at 52 is illustrated in the word "malum" at the right thereof in the upper line. With a dot, said character represents the sound of gh as in the word "maghlub" as shown at the right of 52. Connecting "ef" and "kaf" are produced by the character 53 which may have dots printed adjacent it, as for example, in the word "lefen" shown in the upper line at the right, and the word "mekale" at the right of 53.

Connecting "sin" (connecting on both sides) is shown at 54. Said letter is illustrated as forming part of the word "mesul" at the right. Said letter may be variously combined to produce or represent other signs. It may be combined with dots to form "shin" as shown at the right of 54 in the word "meshhur", and it may also be combined with the letter "noon" to form the independent letter "sin" as shown to the right of 66 in Fig. 3.

Connecting "he" is shown at 55, and is illustrated as part of the word "muhim". Connecting "ha" (connecting only on the right) is shown at 56, and may be combined with various dots as is, for example, illustrated in the word "kelij" at the right of 56. Connecting "ayin" is shown at 57 and illustrated with a dot in the word "tab".

The letter "re" is shown at 59, and is illustrated as forming part of the word "zarar". Said letter is variously combined with dots to represent various sounds. The letter "dol" and medial connecting "dol" are shown at 60 and 61.

Connecting "liam" is shown at 63 where it is illustrated at the extreme right as combined with the two slanting lines to form a Hindustani letter. Said character "liam" is illustrated at the right as forming part of the word "malum".

The letter "re" is shown at 64, and it is always written separately when in this form. It is illustrated as forming part of the word "arslan". The letter "noon" is shown at 66 lacking its dot. Said dot can be inserted by the silent or idle key 28, and

said letter is thus illustrated in the word "liman" at the right. At the extreme right said character 66 is shown as forming part of the letters "sin" and "sod" in one of their forms.

At 69 is shown a sign which always comes between two letters and has a value depending on its associated dots which may vary in position and number. It is illustrated as forming part of the word "sabah", and also as forming part of the word "hayat".

It may also be combined with a comma as above described to form the Hindustani character of the sound ha shown at the right. The character 72 is a square used for a period, and is entirely distinct from the round dot 28 or 38 which has an entirely different significance. Non-connecting "mim" is shown at 74. Terminal connecting "mim" is shown at 75, and is illustrated as forming part of the word "taksim".

It will be noted that some letters are so tall that they project beyond the usual allowable limit of printing. I have found that it is possible to properly print such letters by placing them in the upper case position on the type-heads. It will also be noted that letters connecting on both sides such as "mim" 37, "sin" 54, "sod" 50, "ef" 52, "he" 55, "liam" 63, etc., are all of the same width so that the written line is in proper form. Furthermore, I have provided the proper terminal letters like "mim" 57 and initial letters like "mim" 27, all of which connect properly with other letters and yet are distinctly in the forms which differ from such letters when not connecting.

The word "Allah", for example, may be written by striking the silent key to print the character 1 in the upper case, and then striking the key to write the letter "elif" 19 in the upper case, which will feed the carriage along one space to the right, then writing the character connecting "liam" 21, then striking the silent key 9 to write its character in the upper case, then striking the key 63 to write the connecting "liam" in the upper case, and then striking the key 65 to write the connecting "he" in the upper case. This completes the word "Allah", as shown at the right of the character "elif" 10 (Fig. 3).

It is possible to write some of these languages for which the machine is especially adapted with fewer characters than those provided in the present keyboard. For example, some of the punctuation marks have only recently been adopted by the more progressive communities where these languages are used, and are not used elsewhere. In addition to these, some of the double connecting letters like double connecting "sod", some of the forms of "liam", double connect-

ing "te", and some of the double letters such as "liam mim" may be omitted for writing such a language. Also in writing some of the other languages other characters might be omitted. The keyboard I have provided enables considerably over one hundred characters to be written, and since it provides the acceptable form for every letter in any position in the word, it is advantageous usually to have the full keyboard on the machine.

There are some letters in some of the languages which are frequently used in special forms and can be made by carefully selecting the proper types which have not been described above. Typical of such letters is the Hindustani "liam" which can be made by striking in succession the characters 21, 68 and 30. It will be noted that this character thus printed differs from other "liams" only in its proportions; but the possibility of printing said character gives an excellent idea of the availability of my arrangement of types in enabling special forms of letters to be produced.

As will be clearly seen from the examples given in Fig. 3, the characters which connect to form letters, or which by themselves form letters and connect to form words, all connect along the same horizontal line across the page, thus avoiding the troubles due to having letters connect at any one of several points in their vertical height.

Variations may be resorted to within the scope of the invention, and portions of the improvements may be used without others.

Having thus described my invention, I claim:

1. The combination with typewriter types adapted to form both "te" medial and "te" initial, of typewriter types adapted to form the remainder of the letters of the Arabic alphabet.

2. The combination with typewriter types adapted to form both "the" medial and "the" initial, of typewriter types adapted to form the remainder of the letters of the Arabic alphabet.

3. The combination with typewriter types adapted to form both "sod" medial and "sod" initial, of typewriter types adapted to form the remainder of the letters of the Arabic alphabet.

4. The combination with typewriter types adapted to form the letter "noon" by a letter-feeding and a silent type, of typewriter types adapted to form the letter "sod" by combining with said letter-feeding type, another typewriter type adapted to form the remainder of the letters of the Arabic alphabet.

5. The combination with typewriter types adapted to form the letter "noon" by a letter-feeding and a silent type, of typewriter types adapted to form the letter "sin" by

- combining with said letter-feeding type, and other typewriter types adapted to form the remainder of the letters of the Arabic alphabet.
- 5 6. The combination with typewriter types adapted to form the letter "noon" by a letter-feeding and a silent type, of typewriter types adapted to form the letter "shin" by combining with said letter-feeding type, and 10 other typewriter types adapted to form the remainder of the letters of the Arabic alphabet.
7. The combination with typewriter types adapted to form both connected and unconnected terminal "liam," of other typewriter types adapted to form the remainder of the letters of the Arabic alphabet.
8. The combination with typewriter types adapted to form both medial connecting "doll" and medial connecting "liam," of other typewriter types adapted to form the remainder of the letters of the Arabic alphabet.
9. The combination with a Turkish comma, of a sign to combine therewith to form the Persian letter "eh."
10. In a typewriting machine adapted to write a language of the Arabic type, the combination with letter-feeding types printing complete characters, and letter-feeding types adapted to print incomplete characters, of a type adapted to print a dot to be associated with another character to modify its signification, and another dot differently formed and printed by another type to stand for a period.
11. In a typewriting machine adapted to write a language of the Arabic type and comprising letter-feeding keys, the combination with a letter-feeding key adapted to print the second letter of the Arabic alphabet, and a letter-feeding key adapted to print an additional tail therefor, of keys for printing dots to be associated with said letter and tail for giving said letter and its tail signification.
12. In a typewriting machine adapted to write a language of the Arabic type, the combination with letter-feeding keys adapted to print characters and letters to connect with other letters and a letter-feeding key adapted to write the letter connecting "liam-mim," of a letter-feeding key adapted to write the letter "liam" connecting on one side only.
13. The combination with a typewriter type to form non-connecting "mim," of typewriter types adapted to form terminal connecting "mim" and the remainder of the letters of the Arabic alphabet.
14. The combination with a single typewriter type adapted to write terminal connecting "mim," of typewriter types adapted to write a plurality of other forms of the letter "mim," and the remainder of the letters of the Arabic alphabet.
15. The combination with a single typewriter type adapted to write terminal connecting "ha," of typewriter types adapted to write other forms of the letter "ha," and the remainder of the letters of the Arabic alphabet.
16. The combination with a single typewriter type adapted to write "mim-clif," of typewriter types adapted to write the remainder of the letters of the Arabic alphabet.
17. The combination with a single typewriter type adapted to write terminal connecting "kaf," of typewriter types adapted to write the remainder of the letters of the Arabic alphabet.
18. The combination with a typewriter type adapted to form the herein-shown character 11, of typewriter types adapted to form the Hindustani "liam," and the letters of the Arabic alphabet.
19. The combination with a typewriter type adapted to form an incomplete "kaf," of types adapted to form other letters therefrom, and the remainder of the letters of the Arabic alphabet.
